(57) **CLAIM**

The ornamental design for a mobile phone, as shown and described.

DESCRIPTION

FIG. 1 is a rear perspective view of a mobile phone showing our new design;

FIG. 2 is a front view thereof;

FIG. 3 is to rear view thereof;

FIG. 4 is a left side view thereof where the right side view is a mirror image;

FIG. 5 is a top plan view thereof;

FIG. 6 is a bottom plan thereof;

FIG. 7 is a rear view thereof showing the state in which the relevant icons have been emerged on the small LCD display below the rear camera part in order for the user to easily check if they receive a text message, etc.;

FIG. 8 is a rear perspective view thereof showing the state that the small LCD display below the rear camera part disappears when the mobile phone is turned off; and,

FIG. 9 is a rear view of FIG. 8.

The broken lines are for illustrative purposes only and form no part of the claimed design.

1 Claim, 9 Drawing Sheets
